COMBINED SCREEN AND BLIND

Frank Sienicki, Irvington, N. J.

Application June 29, 1940, Serial No. 343,097

2 Claims. (Cl. 189—62)

This invention relates to an improved screen and blind that is adapted for use in the frame of a window or like opening, the blind portion being outside the screen and is thus efficient as a protector for the screen but at the same time can be used for regulating the admission of light and of air.

The invention relates more particularly to the structural features tending to produce an article of this kind that is cheap to make and is easily operated and can be operated from the inside with complete closure against the entrance of insects and a screen portion that is unbroken.

The invention is illustrated in the accompanying drawing in which Figure 1 is a rear view of the improved combined screen and blind. Figure 2 is a front view of the screen and blind with the screen portion broken away. Figure 3 is a section of part of the blind portion with the blinds closed. Figure 4 is a section on line 4—4 in Figure 2. Figure 5 is a section on line 5—5 in Figure 4. Figure 6 is a detail perspective of the binding screw and associated parts.

The device comprises a frame 10 which is usually installed as any screen and can be made of a size to fit the lower part of a window frame or it can be made to fit the whole window frame. It is provided with a screen 11, usually of woven wire and the screen material is held in place at its side edges under two strips 12 of angle iron which are secured to the frame 10 by screws or nails and have a projecting flange 13 which serves as a support for the slats of the blind.

The blind comprises slats 14 which are usually of light metal crimped at one end around pins 15 which are pivoted in holes in the flanges 13. The slats are thus pivotally fixed at one end. The free ends of the slats are crimped around pins 16 which extend beyond the ends of the slats and are pivoted in holes in a bar 17 which bars are aligned with the flanges 13.

This arrangement allows the bars 17 to rest on the flanges 13 when the blind is closed and this prevents the overlapping slats from coming in contact, insuring slight ventilation and preventing clatter and rattle in a strong draught or wind.

One of the pins 16 extends beyond the bars 17 on each side and forms a means for pivotal engagement with the connections such as links

18 which are connected to the ends of the movable screws 19 as at 20. The screws 19 are slideable in slots 21 in the sides of the frame 10 and in the plates 22 which are used in the case of wooden frames to protect the wood. The screws are provided on the outer end of each with a thumb screw 23 which hold the screws 19 in adjusted positions.

The screws 19 are also provided with cover plate 24 which slide with the screws 19 and are long enough to cover the slots 21 at all points of adjustment of the screws. The cover plates are of metal and slide on the outside of the frame 10 and form closure for the slots 21, 21 against the entrance of insects.

In Figure 6 a screw 19 is shown as flattened as at 25 for a portion of its length to fit the slot 21 and prevent tilting and binding at the joint 20 in case of larger or heavier sizes of screen.

I claim:

1. A combined screen and blind comprising a frame, a screen over the opening in the frame, angle irons secured against the outer face of the frame and securing the screen in place, rods connecting the projecting flanges of the angle-irons, slats crimped over the rods whereby the slats are fixedly hinged, bars in the planes of the flanges and adapted to rest against the flanges, rods connecting the bars, the outer ends of the slats being crimped around the last-mentioned rods to form hinged connections, a manually operable stud extending through the side of the frame, and a link connecting the stud with the central part of one of the bars.

2. A combined screen and blind comprising a frame, a screen over the opening in the frame, angle-irons secured against the outer side of the frame and securing the screen in place, rods connecting the projecting flanges of the angle-irons, slats crimped over the rods whereby the slats are fixedly hinged, bars in the plane of the flanges and adapted to rest against the flanges, rods connecting the bars, the outer ends of the slats being crimped over the last-mentioned rods to form hinged connections, one of the rods projecting beyond a bar, a link hingedly connected to said projecting part, and a stud slideable in the frame and hingedly connected to said link.
